UNITED STATES PATENT OFFICE.

LEWIS C. DAVIS, OF BALTIMORE, MARYLAND.

BOILER-WATER-LEVEL AUTOMATIC CONTROL APPARATUS.

Application filed April 3, 1925. Serial No. 20,526.

To all whom it may concern:

Be it known that I, LEWIS C. DAVIS, a citizen of the United States, residing at Baltimore, in the county of Baltimore City and State of Maryland, have invented certain new and useful Improvements in Boiler-Water-Level Automatic Control Apparatus, of which the following is a specification.

10 This invention relates to automatic water level and supply controllers and emergency indicators for steam boilers.

The objects of the present invention are, to provide a very sensitive apparatus which will act quickly and delicately in supplying and shutting off the water supply; to provide an apparatus which will control the supply of water in such manner that the water will be admitted in small quantities and with great frequency and will guard against a large body of water being supplied at any one time in order to avoid cooling of the whole body of water in the boiler; to provide a pressure controlled apparatus as distinguished from a thermostatic control; to provide means for sealing the pressure element, water, in the generators of the apparatus; to provide easy means for replenishing the pressure element, water, in the generators from the boiler water; to provide a control apparatus wherein the pressure generators will require refilling only at long intervals; to provide quick, simple and certain means for venting the pressure generator systems; to provide simple and cheap and quickly replaceable diaphragms in the control apparatus; to provide a construction wherein the diaphragms will be so located as to be guarded against the action of heat; to provide a lever and connecting means operated by a diaphragm for operating a lever or other operative part, which may be connected to a water supply valve for supplying water to a boiler or battery of boilers, or to a steam valve for governing the supply of steam to the steam motor of a water pump, or to an electrical switch or other element for the purpose in view; to provide a second lever as an emergency device, which, on the continued lowering of the water level, will be actuated by an independent pressure generator to sound a signal or bring signal or other indicating means into operation and to provide means, which may be said second lever, operated by said independent pressure

generator, for also operating said water control means, all as hereinafter more particularly set forth, described and claimed.

In the accompanying drawing, illustrating merely one embodiment or arrangement of my invention, but without any wish or desire to be understood as being limited thereto:

Figure 1 represents a front elevation of 65 a boiler with apparatus embodying my invention applied thereto;

Figure 2, a top plan view of the upper pipes or inclined chambers 5 and 6 and bypass 7, with the water column connecting 70 tubes 2 and 4 connected thereto and broken away, and showing the pressure generator tubes 8 and 9 combined therewith; and

Figure 3, a longitudinal sectional view through the diaphragm chambers 13 and 14 75 and connecting pipe 15, showing the tubes 8 and 9 and the supply pipe 16 broken away.

While one embodiment of my invention is shown and described in detail, the pipes or chambers 5 and 6 being shown as arranged with a common axial line, it is to be understood that it is not essential that said chambers should be thus arranged, it being sufficient if the chamber 6 be arranged on a lower level than chamber 5 and that there be an unobstructed passage from one to the other, and so long as this feature is regarded they may be arranged in any one of a number of different ways. The actual form or 80 appearance of the apparatus is governed in large part by the space available adjacent the boiler, the arrangement of the parts being such as to conform to the space available, as will be obvious to one familiar with the 85 art.

Referring now in detail to the drawings, A indicates a conventional boiler, B the usual water supply pipe thereof having a hand valve C, D the usual water column having the usual indicator or sight glass or gage E; F indicates a whistle mounted on the top of the water column D and adapted to be blown by steam from the top of the water column D and the top or dome of the 100 boiler A upon the proper actuation of the whistle lever G; H indicates a pipe leading from the top of the boiler A to supply steam to a steam engine, not shown, to operate a water pump, not shown, of any usual construction, to force water through the supply pipe B so long as the valve operated by the 105

lever I remains in open position; and J represents a weight hung on lever I for holding it normally in closed position. Of course, any equivalent means, having the same general function, that is, closing the valve operated by lever I and maintaining it normally closed, may be substituted for the weight J.

The water column D in usual practice is provided with three test pet-cocks, so that in case the indicator glass or gage E should break the operator could cut it out and still tell as to the level of the water in the boiler by the test pet cocks and so continue the boiler in operation with safety. These pet cocks are arranged at three different levels to indicate normal water level at pet-cock L, the highest pet-cock; low water level at pet-cock M, the middle pet-cock; and dangerously low water level at pet-cock N, the lowest pet-cock, so that by operating the valves L, M and N respectively of said pet-cocks the operator can tell by the escape of steam or water whether the water level is above or below the particular pet-cock.

In the practice of my invention I prefer to apply it to the boiler water column D by removing the upper pet-cock L, screwing one end of the head of a T-coupling 1 into or onto its bore or nipple in or on the water column D, screwing the pet-cock L on the other end of the head of said T coupling 1, and connecting the small pipe or preferably copper tube 3 to the end of the stem, and to similarly connect the small pipe or preferably copper tube 4 by means of a T-coupling 2 between the water-column D and the pet-cock M, so that said tubes or pipes 3 and 4 at all times have communication with the interior of said water-column D at the respective levels of the said pet-cocks L and M and with the interior of the boiler through the said water-column D, which is connected at or near its top and bottom, respectively, with the interior of said boiler by means of tubes or pipes as usual.

A pipe or chamber 5, preferably lying in a very slightly inclined plane and having no interior portion at a higher level than the interior of the coupling 1, is connected to the latter by the preferably substantially horizontal tube or pipe 3 as shown, and a pipe or chamber 6 having its lowest portion preferably in the same, and in no case below the horizontal plane as the coupling 2, and preferably arranged at a slight inclination, is connected to the latter by the pipe or tube 4, which is preferably horizontal, and the interiors of the pipes or chambers 5 and 6 are in communication with each other through the tubular means or by-pass 7, which may be of elongated U-shape, and of which no part is at a higher level than the lowest part of chamber 5 and no part at a lower level than the highest part of chamber

6, its arrangement being such that there will be a slight drop from 5 to 6 so that water may drain by gravity from 5 to 6 and be replaced as it recedes by steam.

The function of this by-pass 7 is to permit of the draining of water from chamber 5 to chamber 6, so that as the water level in the boiler falls the water in the chambers 5 and 6 may drain from the chamber 5 to chamber 6 and from chamber 6 through pipe 75 or tube 4 back into the water column D, the recession of the water allowing steam, passing through coupling 1 and tube 3 to progressively enter the chambers 5 and 6 as the water level falls to the point where the water level in column D falls below coupling 2 and pipe or tube 4, when all the water will be drained from the chamber 5, by-pass 7 and chamber 6 and they will be filled with steam as above explained.

Of course, as the water level progressively falls a progressively larger surface of the generator tube 8 in chamber 5 will be exposed to the action of steam in chamber 5 to heat the tube 8 and vaporize some of the 90 contents thereof, and this applies also to chamber 6 and generator tube 9 as the water continues to fall, should the primary generator be out of order, until the water level has dropped below coupling 2 when all 95 water will have drained through pipe or tube 4 from the chamber 5, by-pass 7 and chamber 6 back to the water-column D or the boiler, when there will be a free and unimpeded circulation of hot steam through 100 the chambers 5 and 6, that is to say, through tube 3, chamber 5, by-pass 7, chamber 6 and back through pipe 4, resulting in a very rapid generation of steam and pressure in 105 the generator tube 9 with consequent quick responsive operation of the lever 25, pulling on the cable 28 to sound the whistle and simultaneously pulling on the cable 27 to pull the lever 22 and so pull on cable 24 to 110 actuate lever I.

Of course, when the water level is appreciably below coupling 1, but above coupling 2, the water will have drained partially from chamber 5, by-pass 7 and chamber 6, so that, while the chamber 5 might be free of water, or partially free thereof, leaving the generator tube 8 therein exposed, or partially exposed, to the action of the steam, there would be water in the tube 4 and in the chamber 6 and also in by-pass 7, thus blocking a free circulation of steam through the tube 3, chamber 5, by-pass 7, chamber 6 and back by tube 4 to the water column D and the boiler, thus preventing the heating action of the steam on the generator tube 9 in the chamber 6 to generate steam therein so long as the water level in the boiler remains at a point above the highest point of the chamber 6. In such conditions, so long as the chamber 6 is com- 120 125 130 135

pletely full of water, the steam will not enter, as steam, therein, but will act only to heat the generator tube 8 and its contents to generate steam therein, and in so doing 5 will yield up its heat to the tube 8 and its contents and will thereby be condensed. In other words, in these circumstances, there will be a continuous condensation of the steam in chamber 5 and a corresponding 10 generation of pressure in the tube 8 due to the heating thereof and the generation of steam therein, the condensate returning to the boiler with the water through the lower pipe or tube 4.

15 The pipe or chamber 5 will have its ends sealed or plugged or otherwise closed and will preferably be of relatively large internal diameter, preferably three-fourths of an inch in internal diameter, and has extending through it a tube 8, preferably of copper, and preferably one-half inch in external diameter, said tube 8 being normally out of communication with the interior of chamber 5 and having its ends extend beyond the closed ends of chamber 5, as shown.

The pipe or chamber 6 will preferably be of the same size and construction as the chamber or pipe 5 and has similarly extending through it and beyond its ends a tube 9, also preferably of copper and preferably of three-eighths inch external diameter, being appreciably smaller in diameter than tube 8, in order to provide a greater space or chamber for a greater body of heating 30 medium, steam, and a smaller space for a smaller column or bar of water to be heated by the steam in order to expand and generate pressure with greater rapidity in the emergency pressure generator tube 9.

40 The adjacent ends of the tubes 8 and 9 are connected by a coupling 10 provided with a valve 11 for normally preventing communication between said tubes 8 and 9, while permitting such communication between said tubes for purposes of filling or 45 refilling them.

The other end of tube 8 is bent downward and coupled to nipple 12 of diaphragm chamber 13, while the other end of tube 9 is similarly bent downwardly and similarly connected to the nipple 12 of diaphragm chamber 14.

50 A hand operated valve controlled vent 17 is interposed in the tube 8, and at its highest point, between the chamber 5 and nipple 12 of chamber 13.

A tubular rod or pipe 15 is interposed between, and connected to, the diaphragm chambers 13 and 14, being sealed off from, and out of communication with, chamber 13 by means of a suitable plug or other equivalent means, and normally sealed off from communication with chamber 14 by means of the valve or turn-plug 29. This rod or pipe 15 serves to maintain the spaced rela-

tion of the chambers 13 and 14 and the levers 22 and 23, and also to establish communication between pipe 16 and chamber 14 for purposes of refilling. However, both of these functions may be accomplished in any 70 one of a variety of ways, the rod or pipe 15 extending from the chamber 13 to the chamber 14 is not essential for purposes of spacing this may be accomplished by securing against a wall or in any other obvious manner, and any valve controlled means of communication between pipe 16 and chamber 14 may be substituted for that of the structure shown.

The interior of pipe 15 is in communication with chamber 6 by means of connecting pipe 16, so that, pipe 15 being at a lower level than chamber 6, pipe 15 is always full of water. This pipe 15 is provided with a small drain cock 18 for the purpose of draining off sediment from time to time as may be necessary, or for draining the water from the pipes 15, 16 and from the generator tubes 8 and 9.

In each diaphragm chamber 13 and 14 is suitably held in usual manner a preferably rubber diaphragm 19 which bears against the foot 20 of a rod 21 working through the outer end of said diaphragm chamber, the rod 21 of chamber 13 bearing against the lower end of lever 22 having a short operating arm and adapted to turn it on its pivot 32 mounted in its arm 33 to pull on the cable 24 passing about pulley 25 to swing lever 1 upward to move its valve to open position to cause water to be supplied to the boiler; and the rod 21 of chamber 14 bearing against the lever 23, having an arm preferably approximately twice the length of the operating arm of lever 22, to operate or pull on cable 24 by cable 27 and lever 22 if the latter should fail of operation by the diaphragm of its diaphragm chamber 13, and to pull on cable 28 to operate the whistle or other warning signal to notify the operator that the normal water controlling pressure generator was out of order.

The copper tubes 8 and 9 are filled with water and each, with its diaphragm chamber 13 and 14 and its encasing pipe or chamber 5 and 6 respectively, constitute a normally separate and distinct pressure generating and actuating automatic control system, the tube 8, pipe 5 and diaphragm chamber 13 and operative parts constituting the 115 normal water control pressure generating system, and the smaller diameter tube 9, pipe 6 and diaphragm chamber 14 and operative parts constituting the emergency water control and signal operating pressure 120 generating system, the two systems being adapted to be temporarily put in communication with the interior of the pipes 5 and 6 and by-pass 7 by valve 29 and with each other by valve 11 for the purposes of flushing 130

and replenishing the water in the two pressure generating systems, the valve of the air-vent 17 being opened at the same time to ensure the escape of all air from both pressure generating systems.

To start up operation, assuming that the boiler is empty and the invention has just been applied thereto:

The boiler will be filled with water and 10 during such period the valve 11 and valve 29 and valve of air-vent 17 will be left open, so that as the boiler fills and the water level rises in the water-column to and above coupling 2 water will flow along tube or pipe 4 to chamber 6, through the latter to pipe 16, to pipe 15, through valve 29 to diaphragm chamber 14, up tube 9, through valve 11 to tube 8, to air-vent 17, down pipe or tube 8 to diaphragm chamber 13, filling the latter, 15 any air in the tubes 8 and 9 of diaphragm chambers 13 and 14 of the two pressure generating systems escaping through vent 17. Of course, as soon as the pipes 15 and 16, the diaphragm chamber 14 and curved outer 20 end of tube 9 are filled, the chamber 6, bypass 7 and chamber 5 will be filled progressively and to the same level as the water rises simultaneously with the filling of the remained of tube 9 and tube 8, until the water level in the water-column D and boiler 25 rises slightly beyond or above the top of coupling 1, when the supply of water is to be shut off. Thereafter the valves 11 and 29 and the valve of air-vent 17 will be left open 30 for a short period, somewhat less than a minute will suffice, to be certain that the diaphragm chamber 13 is filled and all air is vented from the two pressure systems. The valves 11 and 29 and valve of air-vent 17 35 will then be closed, resulting in sealing the water in each pressure generator tube from that in the other pressure generator tube, from the atmosphere, and from the water in the pipe 15.

40 The fire will then be started up and as the water is heated and steam generated the level of the water will drop until the end of coupling 1 is uncovered, allowing steam to pass therethrough and through tube 3 into the chamber 5 as the water therein recedes with the lowering of the water level in the column D, such steam heating the water in the tube 8 and turning some of it 45 into steam with resultant expansion and creation of pressure in the tube 8 and diaphragm chamber 13, thrusting outwardly or endwise against its diaphragm 19 and through the diaphragm 19 against foot 20 of its rod 21, which rocks lever 22 to pull 50 on cable 24 to start the water supply. As the water is supplied it, as its level rises and 55 so fills the chamber 5, excludes or drives out the steam and cools the water in tube 8, condensing the steam therein and so reducing 60 the pressure therein, allowing the lever 22

and the lever I of the water control valve to drop back to normal closed position under the influence of weight J or equivalent means.

However, assuming, for instance, that the diaphragm 19 in chamber 13 has given way or been ruptured, so rendering the normal water control pressure generating system 70 inoperative, the water level will continue to fall, and the level of the water in chamber 5, bypass 7 and chamber 6 in accord therewith, allowing steam to work around through bypass 7 into chamber 6, when it will act to heat quickly the smaller copper tube 9 and to generate steam therein with 75 consequent rapid generation of pressure in the emergency water control and signalling pressure generating system, resulting in operating the lever 23 to, through cables 27 and 24, operate lever I and to pull on cable 80 31 to operate the whistle or other signal.

Since the tubes 8 and 9 and their diaphragm chambers 13 and 14 respectively are hermetically sealed there is no opportunity 90 for any appreciable loss of contents by means of evaporation, so that they require refilling only at very infrequent intervals. In use I have found that refilling of such pressure generators once a month was sufficient over a period of a number of months. 95

In applying the diaphragms 19 they will not be stretched, but on the contrary will be left sufficiently slack so that they may flex, without stretching, for the full amount of 100 their deformation under greatest pressure conditions, in order that their material be not called upon to actively resist the pressure generated, but merely to act as a flexible seal for the end of the chamber, thereby prolonging their period of usefulness. 105

Having thus described my invention, what I claim as new and desire to secure by Letters Patent is:

1. In a boiler water level automatic control apparatus, a chamber, means forming 110 communication between the interior of the boiler and said chamber, and means for forming communication between the boiler and said chamber at a lower level so that as the water level lowers in the boiler the water in said chamber will drain therefrom, in accordance with the water level, through the latter means, allowing steam to enter said chamber from the boiler through the former means, and so that as the water level rises the inflow of water through the second mentioned means will drive the steam from said chamber through the first mentioned means, in combination with a container normally sealed and extending in said chamber, an operative agent in said container of such nature as to be acted upon by the heat of the steam thereon and so caused to expand 115 to generate pressure in said container and to be condensed back to normal by immer- 120

125

130

- sion of the container in water of normal boiler temperature, means actuated by the expansion of said agent in said container for causing the supply of water to the boiler 5 until the water level has been raised sufficiently to drive the steam out of said chamber and act on said container to cool the agent therein to reduce the pressure therein, and means adapted to put said chamber and 10 said container temporarily in communication to fill said container.
2. In a boiler water level automatic control apparatus, a chamber, means forming communication between the interior of the boiler and said chamber, and means forming communication between the interior of the boiler and said chamber at a lower level so that as the water level lowers in the boiler the water in said chamber will drain 15 therefrom, in accordance with the water level, through the latter means, allowing steam to enter said chamber from the boiler through the former means, and so that as the water level rises the inflow of water 20 through the second mentioned means will drive the steam from said chamber through the first mentioned means, in combination with a container normally sealed and extending in said chamber, water in said container, means actuated by the expansion of the container water when under the influence of steam in said chamber for causing the supply of water to the boiler until the water level has been raised sufficiently to 25 drive the steam out of said chamber and act on said container to cool the water therein to reduce the pressure therein, means adapted to put said chamber and said container temporarily in communication to fill said 30 container, and means for venting the air from said container as it is being filled with water.
3. In a boiler water level automatic control apparatus, a primary chamber, a steam supply pipe forming communication between said chamber and the boiler, a tube extending through said chamber and sealed therefrom and adapted to contain water, a diaphragm chamber in communication with said tube and a diaphragm therein and closing the same, said water in said tube being adapted 35 to be partially vaporized by steam entering said chamber through said pipe to generate pressure in said tube and diaphragm chamber to cause movement of the operative portion of said diaphragm, and means operated by said diaphragm to control the boiler 40 water supply, in combination with an emergency chamber arranged at a lower level than said primary chamber, a by-pass forming communication between said chambers, a pipe forming communication between the 45 lowest portion of said emergency chamber and the boiler on a level at least as low as said portion, an emergency tube extending through said emergency chamber, sealed therefrom, of smaller diameter than the first 50 mentioned tube, and adapted to contain water, a diaphragm chamber in communication with said emergency tube, a diaphragm therein and closing the same, a signaling means, means adapted to be operated by the 55 movement of the last mentioned diaphragm to operate the boiler water supply means and to operate said signaling means, said tubes being normally sealed off from each other, and means for temporarily establishing communication between said tubes and between 60 said tubes and chambers and between said tubes and the atmosphere, for the purpose of refilling said tubes and diaphragm chambers with water and for venting all air from 65 said emergency chamber and the boiler on 70 75 80 85 90 95 100 105 110 115 120 125 130

said tubes and said diaphragm chambers. 5. In a boiler water level automatic control apparatus, a primary chamber, an emergency chamber arranged below said primary chamber, a by-pass establishing continuous communication between said chambers, tubular means forming communication between said primary chamber and the boiler at the normal boiler water level, and tubular means forming communication between said emergency chamber and the boiler at a lower level, in combination with a primary control means comprising a tube having a portion extending through said primary chamber, an active agent sealed in said means and partially contained in said tube and of such nature as to be expanded by the heat of steam in said primary chamber to generate pressure in said means and cooled by water as it rises in said primary chamber to eliminate pressure in said means, and water supply means controlled by the variations of pressure in said means; an emergency control and signaling means comprising a signal, a tube having a portion ex-

tending through said emergency chamber, a similar active agent sealed in the emergency means, a movable part actuated by the variations of pressure in said emergency means, a supplemental element connected to said movable part to operate the water supply means, and means connecting said movable part to said signaling means; the tubes of said primary and emergency control means being sealed off from each other normally so that their active agents will normally act independently of each other, means for establishing communication between said tubes, and between said tubes and said chambers for refilling the primary and emergency control means, and means for venting the air from said primary and emergency control means through the highest point of said tubes when said tubes are in communication with each other.

In testimony whereof, I have signed my name to this specification at Washington, D. C., this 3rd day of April, 1925.

LEWIS C. DAVIS.
